UNITED STATES PATENT OFFICE.

HOWARD D. MATTHEWS, OF MANSFIELD, OHIO, ASSIGNOR TO WESTINGHOUSE ELECTRIC & MANUFACTURING COMPANY, A CORPORATION OF PENNSYLVANIA.

THERMAL RELAY.

Application filed April 28, 1925. Serial No. 26,333.

My invention relates to thermal protective means and particularly to thermal relays.

One object of my invention is to provide a relatively simple and compact thermal relay that shall embody means for effecting a variable time delay of operation of the device in accordance with the voltage of an energy translating device with which it is operatively associated.

Another object of my invention is to provide a thermal relay that shall permit of being employed with any one of a number of energy translating devices having the same current capacity but different voltage capacities.

In practicing my invention, I provide a pair of cooperating contact members so mounted that they are respectively actuated by bimetallic, current-traversed elements. One of these bimetallic elements is connected in series circuit relation to the energy translating device and the other bimetallic element is connected in shunt circuit relation thereto. Restraining means is provided for each of said bimetallic elements, and the assembly is mounted in a suitable casing.

In the single sheet of drawings,

Figure 1 is a view, partially in section and partially in side elevation, of a device embodying my invention,

Fig. 2 is a partial sectional view thereof, taken on the line II—II of Fig. 1,

Fig. 3 is a partial sectional view thereof, taken on the line III—III of Fig. 1,

Fig. 4 is a diagram of connections employed with the device embodying my invention,

Fig. 5 is a schematic diagram illustrating the relative positions of the contact members under various operating conditions,

Fig. 6 is a diagram illustrating the heating curves of two different sizes of energy translating devices, and

Fig. 7 is a diagram illustrating the effective heating curves of the device, for two conditions of operation.

A thermal relay 11 comprises a lower casing 12 and an upper casing 13, that are of suitable size and construction to support and receive therein shafts 14 and 15 that may be located in substantially vertical position and that are preferably located coaxially. Lower bearing members 16 and 17 and upper bear-

ing members 18 and 19 are provided for the two shafts and are of any suitable construction usually employed in the art.

The shaft 14 has mounted thereon a bimetallic element 21 of relatively heavy cross-section and of spiral form. The inner end of the member 21 is suitably mounted on and secured against the shaft 14, and the outer end thereof is secured against a lug member 22 supported by the casing 12 or by a member mounted therein. For purposes of adjustment, the member 22 may be provided with an adjusting means in a manner well known in the art.

The restraining means 23 comprising a spiral wound spring member, has its inner end secured to the shaft 14 and its outer end secured against an adjustable lug 24 that is supported by the casing 12. A movable contact arm 25 of substantially L-shape, has one end thereof secured on the shaft 14 and is of such length that it extends through a suitable opening 26 in one side of the casing 12. The shaft 15 in the upper casing 13, has mounted thereon a bimetallic member 27 that is of relatively small area in lateral section and is also of spiral form, with its inner end secured against the shaft 15 and its outer end secured against an adjustable lug 28.

A spring member 29, of substantially the same form as the member 23, has its inner end secured against the shaft 15 and its outer end against a suitable stop member not shown. A movable contact arm 31, of substantially L-shape, has one end thereof mounted on the shaft 15, an insulating collar 32 being located therebetween and extends through an opening in the casing 13. The outer end of the member 31 is provided with a suitable contact terminal that is adapted to engage a cooperating contact terminal on the arm 25.

Fig. 4 of the drawings illustrates a diagram of connections employed with the device embodying my invention. An energy translating device 33, here illustrated as an electric motor, but which may be any other electric energy translating device, such as a transformer or generator, is energized from suitable supply circuit conductors 34 and 35 through a circuit controlling means 36, here shown as a two-pole circuit interrupter. The circuit interrupter 36 is provided with an actuating coil 37, that is adapted, when energized, to attract a core member 38 opera-

tively connected to the mechanism of the circuit interrupter to interrupt the circuit through the energy translating device 33. An adjustable resistor 39 is provided that is connected in series circuit relation with the spirally wound voltage thermal element 27, in order to permit of adjusting the current strength traversing the element 27.

The outer end of the bimetallic member 21 10 has connected thereto the end of a conductor 41, the other end of which is connected to the supply circuit conductor 34, a conductor 42 being provided to connect not only to the movable contact arm 25 but also to the inner 15 end of the bimetallic element 21, suitable provision being made to effect an electrical connection therebetween on the shaft 14.

A conductor 43 has one end thereof connected to the supply circuit conductor 35 and 20 the other end to one terminal of the adjustable resistor 39, the other terminal of which is connected by a conductor 44 to the inner end of the spirally wound bimetallic element 27. In order to effect such connection, 25 it may be necessary to provide a collar member 45 on the shaft 15 that is insulated from the other portions of the shaft but is in electrical connection with the inner end of the bimetallic member 27. The outer end of the 30 bimetallic member 27 is connected by a conductor 46 to the supply circuit conductor 34. The movable arm 31 is connected by a conductor 47 to one terminal of the actuating coil 37, the other terminal thereof being connected to the supply circuit conductor 35.

Figure 6 of the drawings illustrates the heating curves of two translating devices such as electric motors. Curve 48 is that of a relatively small machine and is here assumed to be that of a motor adapted to operate on a 110 volt circuit. Curve 49 illustrates the heating curve of a larger machine, which is assumed to have the same current capacity as the motor having the heating 45 curve 48, but adapted to be operated from or connected to an electric circuit of higher potential, such as 220 to 440 volts, or even higher. It is evident that the machine having the same current capacity but adapted to 50 be operated from a circuit of higher voltage, will be larger and will have a larger output for a given speed and will heat up more slowly than the smaller machine adapted to be operated from a circuit of relatively low 55 voltage.

The device embodying my invention has been designed to permit its use on energy translating devices of substantially the same current capacity, thereby simplifying the 60 adjustment of such a device and also permitting of the manufacturer carrying a smaller number of such thermal relays in stock to meet the demands of the varying sizes of motors.

Fig. 5 of the drawings illustrates the po-

sitions of the respective lever arms 25 and 31 when the thermal relay 11 is connected to circuits of different voltages as illustrated in Fig. 4.

The point 51 illustrates the position taken 70 by the lever arm 25 when it is traversed by substantially the same current, while the points 52, 53 and 54 indicate the respective positions of the lever arm 31 when the bimetallic spiral 27 and the resistor 39 are 75 traversed by a current that is substantially in accordance with the voltages indicated in Fig. 5, namely, 110, 220 and 440 volts.

If an energy translating device of relatively small size is traversed by an overload 80 current for a predetermined length of time, it will heat up more quickly than will a larger energy-translating device. When the bimetallic spiral 21 is traversed by an excessive current, the lever arm indicated by the 85 point 51, will move toward the point 52 and the two lever arms will finally operatively engage, that is, provided the overload current continues for a long enough period of time. The actuating coil 37 will thereby be 90 energized and the circuit breaker 36 will be operated to deenergize the energy translating device 33.

If such a thermal relay is employed for an 95 energy translating device of the same current capacity, but of higher voltage, say 220 volts, the position of the lever arm 31 will be moved farther away from the lever arm 51, say to the point 53 and it will require a 100 longer time to effect operative engagement between the two lever arms under the influence of an overload current traversing the bimetallic spiral 21. If the thermal relay is employed with an energy translating device connected to a 440 volt circuit, the arm 31 105 will move to the position indicated by the point 54 and it will require a still longer time to effect such operative engagement.

It is assumed, of course, that the construction of the cooperating parts of the thermal relay embodying my invention is such that the movement of the relay arm 25 under the influence of the bimetallic spiral member 21 110 is great enough to finally effect engagement with the contact member on the arm 31.

Fig. 7 of the drawings illustrates what 115 may be termed the effective heating curves of the device for two different conditions of operation and shows the relative time required to effect operative engagement of the 120 cooperating contacts.

It may be here pointed out that the device 125 embodying my invention is effective in case of reduced voltage on the circuit, to properly protect the energy-translating device. Certain types of motors are traversed by an increased current when the voltage is reduced at the terminals thereof, and this effects a quicker heating of the motor.

The arm 31 will move into a position in- 130

- termidate the points 52 and 51 when the voltage applied to the energy translating device is reduced. If the current value is simultaneously increased, the movement of the arm 25 will be hastened and the two arms will operatively engage much sooner than would otherwise be the case. By proper design and adjustment of the spring member 29 relatively to the element 27, it is possible to effect engagement of the contact members on the arms 25 and 31 when the voltage on the energy translating device has been reduced to a predetermined percentage of the normal value.
- 15 The device embodying my invention thus provides a relatively simple and compact two-part thermal relay comprising one thermostatic element that is subject to the current traversing an energy translating device and a second thermostatic element that is subjected to the voltage of the energy translating device in order to effect an operation of the device that is in accordance with the amount of energy being translated in the energy translating device.
- 20 By adjusting the position of the outer ends of the bimetallic spirals 21 and 27, it is possible to obtain any predetermined time delay in the actuation of the contact members and substantially the same effect may be obtained by adjusting the resistor 39 that is connected in series circuit relation with the bimetallic spiral 27. The time delay in the operation of the device will be therefore in substantially direct accordance with the voltage of an electric circuit to which an energy translating device controlled thereby is connected, particularly so as the operating mechanism is located in a casing whereby it is heat-insulated and not affected by radiation from the outside walls of the casing.
- 25 Various modifications and changes may be made without departing from the spirit and scope of the invention, I desire, therefore, that only such limitations shall be placed thereon as are imposed by the prior art.
- I claim as my invention:
1. A thermal relay for an energy-translating device, comprising a plurality of shafts, spring restraining means for each of said shafts, a plurality of cooperating contact members carried by said shafts, a bimetallic element associated with one of said shafts for actuating the same in accordance with the current traversing said energy-translating device, and a second bimetallic element associated with the second shaft for actuating the same in accordance with the voltage of said energy translating device.
2. A thermal relay for controlling an electric translating device, comprising a shaft, a spring-restraining means therefor, a contact member mounted on said shaft, a spirally-wound bimetallic element having one end fixed and the other end secured to said shaft, said spirally-wound element being adapted to actuate said shaft and contact member to a predetermined position in accordance with the voltage of said translating device, a second shaft co-axial with said first shaft, a spring-restraining means therefor, a contact member on said second shaft, and a second spirally-wound bimetallic element having one end thereof fixed and the other end secured to said shaft, the second bimetallic element being adapted to actuate the second shaft and contact member into engagement with the contact member mounted on the first-named shaft when a predetermined value of current has traversed the translating device for a predetermined length of time.

In testimony whereof, I have hereunto subscribed my name this 23rd day of April 1925.

HOWARD D. MATTHEWS.
